T. GORE

ROPE

Filed Sept. 25, 1926

Inventor
Thomas Gore

By his Attorney

W. W. Beeken

UNITED STATES PATENT OFFICE.

THOMAS GORE, OF BROOKLYN, NEW YORK

ROPE.

Application filed September 25, 1928. Serial No. 137,671.

This invention relates to ropes of the kind generally referred to as turn cables, bull ropes or transmission ropes and has for its main object and feature the provision of 5 means whereby the diameter of such ropes may be decreased while at the same time the tensile strength and the wearing qualities of said rope may be increased.

In the accompanying drawing the invention is shown in two concrete and preferred 10 forms in which:

Fig. 1 is a view in elevation, with successive layers removed, of one of the strands of which the rope is composed showing one 15 form of the invention.

Fig. 2 is a cross-sectional view of the strand substantially on the plane of line 2-2 of Fig. 1.

Fig. 3 is a view in elevation of a rope embodying one form of the invention, with one 20 of the strands stripped.

Fig. 4 is a transverse sectional view through the rope, substantially on the plane of line 4-4 of Fig. 3.

Fig. 5 is a view in elevation, with successive layers removed of a strand embodying 25 a modified form of the invention.

Referring particularly to Figs. 1 and 2, numeral 10 indicates a fibrous core, 11 is an 30 intermediate layer of helically wound flat-rolled wire, and 12 is an outer covering of fibrous material. The component parts of the core may vary but are preferably laid parallel to the axis of the strand. In Fig. 35 1 the core consists of twisted yarns 13 and in Fig. 5 of so-called slivers 14. The intermediate layer of flat-rolled wire is laid helically around the core and is, as will be noted, devoid of any sharp corners. The 40 outer covering is of fibrous material preferably laid helically.

It will be seen from the foregoing that the intermediate layer of flat-rolled wire increases the tensile strength of the strand so 45 that I am enabled to reduce its diameter and at the same time obtain the same or greater tensile strength than heretofore; also the wearing qualities of the rope are increased because there are no sharp corners or thin

round wires to abrade or bruise the fibrous 50 material.

The strands thus produced may be formed into a rope in any of the conventional ways. For instance, as shown in Figs. 3 and 4, a plurality of such strands 55 may be twisted together, either regular lay or Lang lay. In the present instance three such strands are twisted together. As a result of the construction the diameter of the rope can likewise be diminished without 60 sacrificing strength or wearing qualities.

I claim:

1. A strand including a fibrous core, an intermediate layer of tensile strength helically wound flat-rolled wire, and an outer 65 covering of fibrous material.

2. A strand including: a fibrous core, an intermediate layer of tensile strength helically wound flat-rolled wire, and an outer 70 covering of helically laid fibrous material.

3. A strand including: a fibrous core the component parts of which are laid parallel to the axis of the strand, an intermediate layer of tensile strength helically wound flat-rolled wire, and an outer covering of 75 fibrous material.

4. A strand including: a fibrous core the component parts of which are laid parallel to the axis of the strand, an intermediate layer of tensile strength helically wound 80 flat-rolled wire, and an outer covering of helically laid fibrous material.

5. A rope including: a plurality of strands twisted together, each strand consisting of a fibrous core, an intermediate 85 layer of tensile strength helically wound flat-rolled wire, and an outer covering of fibrous material.

6. A rope including: a plurality of strands twisted together, each strand consisting of a fibrous core, an intermediate layer of tensile strength helically wound flat-rolled wire, and an outer covering of 90 helically laid fibrous material.

7. A rope including: a plurality of 95 strands twisted together, each strand consisting of a fibrous core the component parts of which are laid parallel to the axis of the

strand, an intermediate layer of tensile strength helically wound flat-rolled wire, and an outer covering of helically laid fibrous material.

8. A rope including: a plurality of strands twisted together, each strand consisting of a fibrous core the component parts of which are laid parallel to the axis of the strand, an intermediate layer of tensile

strength helically wound flat-rolled wire, and an outer covering of helically laid fibrous material.

Signed at Brooklyn, in the county of Kings, and State of New York, this 16th day of Sept., 1926.

THOMAS GORE.
